UNITED STATES PATENT OFFICE.

HENRY J. FORTIER, OF LOWELL, MASSACHUSETTS, ASSIGNOR, BY MESNE ASSIGNMENTS, OF ONE-HALF TO GARDNER W. PEARSON, OF LOWELL, MASSACHUSETTS.

SPINNING FRAME.

Application filed March 30, 1921. Serial No. 456,836.

To all whom it may concern:

Be it known that I, HENRY J. FORTIER, a citizen of the United States, residing at Lowell, in the county of Middlesex and 5 State of Massachusetts, have invented certain new and useful Improvements in Spinning Frames, of which the following is a specification.

This invention relates to improvements in 10 spinning machines, particularly those having builder mechanisms wherein a ring rail or other builder rail is so connected with the lifting weight that it tends to rise, and so connected with the chain attached to 15 building mechanism of any well known type that the chain operates to lower the rail against the normal action of the lifter weight.

Such spinning machines are adapted to 20 wind yarn on the bobbins, and it is desirable, for use in certain types of looms, that there should be a bunch of yarn wound near the base or head of the bobbin for the purpose of giving better control to the filling feeler 25 mechanism used particularly in certain types of automatic looms.

I am aware that various devices have 30 been used for building such bunches on the bobbins while being filled, but I believe that my device is simpler in construction and 35 operation, and is also more positive and flexible.

It is also desirable that the size and location of the bunch should be capable of 40 adjustment, and this also I accomplish by my device.

In the drawings, Fig. 1 is an elevation showing part of a spinning frame from the front, with parts broken away and parts 45 omitted to expose my device in position. The full lines show the position of the parts after the frame has been doffed, and the dotted lines show the position of the parts after the foot lever has been pushed down, locking the parts, and the chain has been wound up, leaving a small amount of slack.

Fig. 2 is a plan view, and Fig. 3 an elevation of my quadrant locking lever removed from the machine and shown as 50 broken to permit of its being shown on a larger scale than in Fig. 1.

Fig. 4 is an elevation as from the left of Fig. 1 showing the detail of the builder cam and builder motion and the attachments 55 necessary for my device. The starting po-

sition of the toes of the cam D are indicated at Y, Y, and the tripping position by the full lines.

Fig. 5 is an elevation, and Fig. 6 an elevation in section, of the builder cam and 60 adjusting connections of a trip pin thereon.

Fig. 7 is a diagrammatic elevation of a quadrant locking lever with a spring means to hold it in contact with the holding arm.

Fig. 8 shows a modification of the locking lever.

Fig. 9 shows another modification of the locking lever.

In Fig. 1 of the drawings, I show a spinning machine which comprises the usual 70 fixed frame A having the ladder 1, which supports a series of spindles 2 suitably driven by whirls 3 in the usual manner and having a builder or ring rail 4 adapted to be moved upward and downward relative 75 to the ladder 1, the ring rail 4 being provided with the usual rings 5 and travelers 6. The ring rail 4 is shown as being provided with raising and lowering mechanism including a series of rods 7 which are connected at their upper ends to the ring rail 4, each being connected at its lower end by means of a suitable joint 8 with the end of an arm 10 of a bell crank lever E, which is pivoted upon a shaft 11 in a bracket 12 extending downwardly from the under side of the fixed frame or of the ladder.

The bell crank lever E is provided with an extension for lifter weight arm 13 which is shown as carrying a suitable counterweight or lifter weight 15. Instead of the lifter weight it is obvious that a suitable spring might be used to counterbalance the weight of the lifter rail.

At the end of arm 10 is a foot pedal K by 95 the operation of which the ring rail can be depressed, and L represents a latch whereby it can be locked in the depressed position.

Connected to and forming part of bell crank lever E is a quadrant 14 of well 100 known form, which extends upwardly at substantially right angles to the arm 10 and is connected to a chain B which extends therefrom and passes over a sheave 16 and thence downward over a roll 17 carried by 105 a rack 18 forming part of the builder mechanism C.

This builder mechanism is of a well known type and is shown as pivoted at 24 to the frame and as having a counterweight arm 110

25 which carries a builder counterweight 26.

The chain B is shown as passing around roll 17 carried by a rack 18 and as being fastened at its end 19 to a relatively stationary part of the builder mechanism.

Through the medium of a worm 20 and key 21, which can be turned by a winder 22, the position of rack 18 can be changed manually, thereby tightening or loosening 10 chain B.

The cam or heart D of well known construction is shown as in operative relation with a cam follower 23 carried by the builder mechanism in such position that, as the 15 cam revolves, it acts upon the follower 23 thereby automatically moving the builder mechanism in such manner that the chain B is tightened or loosened.

The parts hereinbefore described are substantially all old and well known.

In suitable positions in the cam D, I provide a number of slots 30, 30, 30, corresponding in number with the number of heels and toes of the cam, and passing through each 25 slot, adjustable therein by means of a suitable nut 32, is a trip pin 31 for a purpose to be described.

F represents what I will call a quadrant locking lever, which is pivoted to the frame 30 A at 41 so as to rock vertically. This has a short end 42 and a long end 50. Depending from the short end 42 is a locking lever trigger T attached by means of a bolt 43 to short 35 end 42 in such manner that it can be moved horizontally in a slot 48, and by a suitable bolt 44 and slot 49 so that it can be vertically adjusted whereby its bearing end 45 can be adjusted with reference to the pins 31. This trigger T is so adjusted that as 40 each pin 31 moves around with the cam, it will be lifted, thus lifting short end 42 and lowering the long end 50 of the quadrant locking lever F.

In the top of this long end 50 is a latch 45 notch 51 which preferably extends upward at a slope toward the pivot, and rises at right angles on the side toward the long end so as to serve as a latch. The top part of this holding end may be cut away slightly 50 if desired. In this notch I can also locate a stop finger 54 adjustable therein by suitable bolt 52 for a purpose to be described.

Fixed to the quadrant 14 is a quadrant bracket G by means of suitable attaching 55 bolts 60, and extending upward therefrom is a latch holding arm 61 which is preferably enlarged or extended at the top so as to permit of a horizontal slot 62 which, by means of a suitable bearing bolt 64, permits the holding roller 63 to be adjustably carried thereby and to be adjusted in horizontal position.

This holding roller is positioned so that it 60 will rest on top of the long end 50 of lever F and so that, as the quadrant moves, it will

roll over and drop into the latch notch 51 or rather will allow the long end 50 to rise so that the latch notch 51 will engage the roller 63 and hold the holding arm and quadrant in position until released.

Preferably, I also show a latch closing mechanism H to hold the long end of the quadrant locking lever in contact with the holding roller at all times.

This comprises a bar pivoted at 70 to 75 bracket G, including a weight arm 71 on the end of which is an adjustable counterweight 72 and a follower arm 73 which carries at its end a follower roll 74 which bears against the lower side of long end 50 of lever F, thus so tending to keep it raised at all times.

Instead of a weight operated closing mechanism, such as H, I can use a spring, which may be a tension spring S, connected to 50 and any part of frame A, as shown in 85 Fig. 5.

The operation of my device is as follows: The frame is started with the ring rail half-way up and the foot pedal K is pressed down quickly with the foot to force down the ring rail 4 and moves roller 63 until it is caught and held by notch 51 of quadrant locking lever F.

By means of the winder 22 operating on the key 21, most of the slack of chain B is 95 manually wound up, leaving a certain amount of slack, indicated by the dotted line marked X in Fig. 1, and the machine is allowed to operate. The toes 34 move from the position indicated at Y, Y in Fig. 4, the lower toe and the heels 35 moving correspondingly until the bottom toe 34 100 engaging the follower 33 takes up and then release slightly the slack on chain B.

At the same time the trip pins 31 are moving around, one of them gradually lifting the trigger T until the short end 42 is lifted and the long end 50 depressed to a point where the latch roller 63 is released from latch notch 51 of lever F, entirely releasing 110 the quadrant and the bell crank lever E and allowing the spinning machine to continue to operate in the usual manner.

The trip pins 31 and trigger T are so positioned by their adjustments that, except 115 when starting the frame as described, the long arm 50 of lever F will be always depressed when latch roller 63 reaches notch 51, my mechanism being therefore always 120 out of action except when it is desired that it should be operative to hold the ring rail stationary.

The size of the bunch can be regulated by 125 adjusting the position of the trip pins 31 in their slots 30 in cam D, and the position of the bunch can be altered by adjusting the position of latch roller 63 in its slot 62.

The adjustable stop finger 54 can be used in connection with the hand lever 53 in doffing. Just before doffing, foot pedal K is 130

depressed to bring the ring rail well down on the head of the bobbins, so that there will be an excess of yarn which will automatically wind on the spindle when the 5 bobbin is removed, thus catching the yarn thereon ready for the next empty bobbin.

In my device, the finger 54 is so located 10 that it will ordinarily stop roll 63 and therefore arm 61, bell crank lever E, and the ring rail at a point above the head of the bobbin. In order to permit the lowering described, hand lever 53 attached to quadrant lever F is pushed down by hand, while foot pedal K is pushed down by the foot or 15 held by latch L until such excess of yarn is wound on the bobbin head.

Hand lever 53 is then released, and roll 63 rides back over the sloping side of finger 54 and thereafter is prevented by finger 54 20 from moving beyond a certain point, thus limiting the downward movement of the ring rail 4 except when hand lever 53 is pushed down.

My device can be applied in any spinning 25 or twisting frame wherein there is a builder mechanism including a builder cam connected to a bell crank lever or other similar device for raising and lowering the ring rail by means of a flexible connection, such 30 as a chain, which permits the bell crank lever and ring rail to be moved independently of the builder mechanism.

Its essential features are the locking lever 35 pivoted to the frame having a notch at one end in position to engage a holding arm attached to the bell crank lever and at the other end a trigger or other similar device in operative relation with a trip pin or trip pins carried by the builder cam.

40 It is obvious that my device may be modified in various ways whereby the holder arms can be held by the locking lever and released by the action of a trip pin on the cam engaging such a trigger. It is also 45 obvious that various cooperating parts may be made adjustable in the manner described hereinbefore or by other well known equivalent means.

As shown in Fig. 8, instead of having the 50 short arm 42 of lever F on one side of the pivot and the long arm 50 on the other side, I can pivot F from one end at 78 to frame A and attach the trigger T at a point 77 between the pivot and notch 51.

55 This notch 51 is shown as being underneath instead of on top, and the latch holding arm 61 and holding roller 63 are shown as under instead of over latch F. With this construction, the weight of lever F causes it 60 to tend to drop and there is no need of the closing mechanism H or spring S, for when roller 63 is moved to the right to the dotted position, latch F drops by gravity.

As shown in Fig. 9, I may even dispense 65 entirely with the trigger mechanism and trip

pins, and may use a gravity latch F pivoted at one end at 78 to frame A and having the notch 81 at the top slightly cut away so that when the latch holding arm 80 is carried to the right over F, carrying with it pin 84, 70 which takes the place of roller 63, when latch F is lifted manually, the action of the weight 15 acting through the quadrant and pin 84 will hold up latch F and hold back the quadrant until the flexible member or 75 chain B tightens enough to carry 84 over to the right towards the dotted position, when the latch will drop and remain out of action thereafter.

With this device the quadrant can be 80 locked in position until the bunch is built and then, as just described, it will be released and thereafter be out of action until a new bunch is to be built.

I claim:

1. The combination with a spinning machine having a fixed frame and ring rail raising devices including a quadrant movable therewith, a lowering chain attached at one end to the quadrant and at the other end 90 to builder mechanism, said builder mechanism including means to manually tighten the chain and a builder cam adapted to tighten and loosen the chain independently 95 of the manual means, of a quadrant locking lever pivoted to the fixed frame having a notch near one end and a locking lever trigger at the other end, a stop finger carried by the locking lever and projecting into the notch, a trip pin carried by the builder cam 100 in operative relation with said trigger, a holding arm attached to the quadrant, a holding roller carried by said arm in position to ride on the quadrant locking lever and to engage the notch therein, and means 105 to hold the quadrant locking lever in contact with said holding roller.

2. The combination with a spinning machine having a fixed frame and ring rail raising devices including a lifting weight, a 110 foot pedal and a quadrant movable therewith, a lowering chain attached at one end to the quadrant and at the other end to builder mechanism, said builder mechanism including means to manually tighten the 115 chain and a builder cam adapted to tighten and loosen the chain independently of the manual means, of a quadrant locking lever pivoted to the fixed frame having a notch near one end and a locking lever trigger at the other end, an adjustable trip pin carried by the builder cam in operative relation with 120 said trigger, a holding arm attached to the quadrant, a holding roller carried by said arm in position to ride on the quadrant locking lever and to engage the notch therein, and means including an adjustable weight 125 connected to the quadrant locking lever in such manner as to hold it in contact with said holding roller.

105

110

115

120

125

130

3. The combination with a spinning machine having a fixed frame and ring rail raising devices including a quadrant movable therewith, a lowering chain attached at one end to the quadrant and at the other end to builder mechanism, said builder mechanism including means to manually tighten the chain and a builder cam adapted to tighten and loosen the chain independently of the manual means, of a quadrant locking lever pivoted to the fixed frame having a notch near one end and a locking lever trigger at the other end, a trip pin carried by the builder cam in operative relation with said trigger, a holding arm attached to the quadrant, a holding roller carried by said arm in position to ride on the quadrant locking lever and to engage the notch therein, and means to hold the quadrant locking lever in contact with said holding roller.

4. The combination with a spinning machine having a fixed frame and ring rail raising and lowering devices which include

a bell crank lever movable with the ring rail, builder mechanism including a builder cam, and a flexible connection between the builder mechanism and the bell crank lever, of a locking lever pivoted to the fixed frame having a notch near one end and a locking lever trigger at the other end, a trip pin carried by the builder cam in operative relation with the said trigger, and a holding arm attached to the bell crank lever in position to engage the notch of the locking lever.

5. The combination with a spinning machine having a fixed frame and ring rail raising and lowering devices which include a bell crank lever movable with the ring rail, builder mechanism, and a flexible connection between the builder mechanism and the bell crank lever, of a locking lever pivoted near one end to the fixed frame and having a notch near the other end, and a holding arm attached to the bell crank lever in position to engage the notch of the locking lever.

HENRY J. FORTIER.
